UNITED STATES PATENT OFFICE.

ROBERT MACLAREN, OF CULROSS, SCOTLAND.

AUTOMATIC THERMOMETRIC REGULATOR.

Application filed December 23, 1921. Serial No. 524,553.

To all whom it may concern:

Be it known that I, ROBERT MACLAREN, of Blaircastle, Culross, Fife, Scotland, iron-founder, have invented certain new and useful Automatic Thermometric Regulators, of which the following is a specification.

My invention has for its object to provide an automatic regulator for electric, steam or hot water radiators, the same being also applicable for gas, fire alarm devices, refrigerating control and other temperature control uses, and consists in the provision of a variable or fixed thermometric automatic switch operating a relay. This thermometric automatic switch consists of a double U-tube sealed and having a bulb or sphere at or near each end. The larger bulb carries glycerine or other suitable fluid as the medium used for expansion, mercury in the lower portion of the legs and nitrogen or other suitable gas in the remaining upper portions and smaller bulb or sphere. One of the U-tubes carries two or more platinum or other terminals, one in each leg with third terminal to act as a common connection at the bend of the tube. I may also suitably fix screw plungers in the bends of the U-tubes for adjustment purposes so that any temperature range limits can be obtained. The smaller bulb or sphere is inserted to reduce the compression ratio on that side to allow the mercury to move freely. If the automatic switch is to be used with the U-tubes in a horizontal position the bore of the tubes should be small enough to prevent flow of the mercury due to gravity.

Two solenoids are used to operate the radiator regulator valve in the cases of water and steam or such like, or a switch is used if for an electric radiator. The solenoids are automatically brought alternately into play as the temperature surrounding the bulb rises or falls thus expanding or contracting the gas or liquid in the bulb, and thus making or cutting off contact.

The current for operating the solenoids is taken from a battery of cells, or other convenient source of supply.

Suitable provision is made for conveniently connecting the regulator to the radiator system.

It is to be understood that although I have hereinafter described one arrangement for operating the radiator regulator valve or

electric switch, there are many other ways which might be employed without deviating from the principle of my invention.

In order that my invention may be properly understood and readily carried into effect, I have hereunto appended one sheet of drawings, of which—

Figure 1 is an elevation illustrating one form of variable or fixed thermometric automatic switch.

Figure 2 is a plan of Figure 1.

Referring to the drawings, the variable or fixed thermometric automatic switch consists of a double continuous U-shaped tube of glass or other suitable material A, A₁ from 60 one leg A of which branches a sphere B. At the bottom of tubes A and A₁, screw cap plungers D and D₁ are inserted, D to vary range and D₁ to vary limit. From the leg A₁ of the double U-shaped tube a small 65 sphere B₁ branches and the extreme end A₁ is closed or sealed. The lower ends A₃ and A₄ of the U-tubes A and A₁ may be reduced in bore and the junction A₅ of the tubes A and A₁ may also be reduced in bore for convenience in transit. The lower ends of the tubes A₁ and A₂ contain mercury G, glycerine H, or other fluid takes up the remaining space in the leg of the U-tube A which is in connection with the sphere B also filled 70 with glycerine H₁ or other suitable fluid. The remainder of the double U-tube, i. e. the right hand leg of A, both legs of A₁ and the sphere B₁ being filled with nitrogen or other inert gas, the whole of the double U-tube 75 being suitably fixed to the base F. Suitable electric terminals are fixed to the base F at predetermined points being electrically connected by platinum or other suitable material to the inside of the legs of the U-tube 80 A₁ for example at the points a₁, b₁, c₁, shown in Figure 1.

Claims.

- An automatic regulator of the class described comprising a double U-shaped tube and having a bulb or sphere forming part of one of the U-shaped tubes, the other U-shaped tube being also provided with a small sphere or bulb branching therefrom the extreme ends of both being sealed, terminals mounted in the lower ends of one of the U-shaped tubes the switch ends of the tubes being filled with mercury, the remaining space in the leg of the tube together with large sphere being filled with 100 105 110

glycerine or other suitable fluid, while the remainder of the double U-tube and smaller sphere or bulb are filled with nitrogen or other inert gas.

- 5 2. An automatic regulator as in claim 1, characterized by two extensions branching from the bottom of the double U-tubes each having an adjusting screw cap for varying

the quantity of mercury in the legs, one to vary the range and the other the limit. 10

In testimony whereof I affix my signature in presence of two witnesses.

ROBERT MACLAREN.
